(57) **CLAIM**

The ornamental design for a mobile showroom advertising system, as shown and described.

DESCRIPTION

The present application is related to U.S. Ser. No. 15/398, 506, filed Jan. 4, 2017, which is hereby incorporated by reference.

FIG. 1 is a front view of a first embodiment of a mobile showroom advertising system of my design in a closed position;

FIG. 2 is a rear view thereof;

FIG. 3 is a top view therefor;

FIG. 4 is a right side thereof;

FIG. 5 is a left side view thereof;

FIG. 6 is a front view thereof in an opened position;

FIG. 7 is a rear view thereof in an opened position;

FIG. 8 is a top view therefor in an opened position;

FIG. 9 is a right side thereof in an opened position; and,

FIG. 10 is a left side view thereof in an opened position. The broken lines in the drawings depict portions of the mobile showroom advertising system that form no part of the claimed design.

1 Claim, 7 Drawing Sheets
